No 523

ABBOTT & LAWRENCE ASSINEES OF
S H SAILOR DESIGN FOR CANNON STOVE

Patented November 9th 1852.

Samuel H. Sailor of Philadelphia, Pa.

Assignor to

James G. Abbott & Archiles Lawrence of same place

Letters Patent No. 523 Dated Nov. 9th 1852

The schedule referred to in these Letters Patent, and making part of this same —

To all whom it may concern:

Be it known that I, Samuel H. Sailor of Philadelphia, in the County of Philadelphia, and State of Pennsylvania, have invented or produced, a new & original design in the stove called "The Octagon Cannon", and I do hereby declare, that the following is a full, clear and exact description of the same, reference being had to the annexed drawings, making part of this specification, in which

Figure 1 is a perspective view of the stove Figure 2. is a front elevation of the leg.

The bed plate (A) of the stove has around its outer edge a rim, formed in front, by the interlacing of the scrolls (a, a) with the curved sweeps (b, b) terminating in the scrolls (z, z); and upon the back and sides of the scrolls (y, y), arranged as seen in the drawing. In the centre of the front of the rim is the shell ornament (x), and in the corners the ornaments seen at (g, g).

Upon the hearth, within the rim (R) is the inscription

"Abbott & Lawrence

Patented 1852

Philadelphia"

in raised capitals & numerals,

arranged as is seen in the drawing.

The lower part (B) of the body of the stove, containing the ash box has its faces curved, as seen in figure 1; and has on each of them the ornament (b'). The ornament in front, is in the panel

formed by the moulding (3) upon the door of the ash hole, and has in its centre the handle (3') as seen in the drawing.

Upon the corners of the part (B) of the stove are the curved ornaments seen in the drawing at (c,c).

Resting upon the lower part (B) of the body of the stove, is the grate plate (C) ornamented in front by the foliage (e), the sweeps (r), and the figures (d), and upon the sides and back by the figures (e', e''); all combined and arranged as seen in the drawing. In each corner of the top of the plate (C) is the ornament seen at (g).

Above the grate plate (C) is the octagon frame (D), enclosing the barrel of the stove. This frame is of open work, and has at each of its corners the figures (h, h') between which, and entwined with them, are the figures (h, h') arranged as seen in the drawing. Interspersed with the figures (h, h') in the manner shown in figure 1, are the scroll shaped figures (g, g'), in which are the pendant figures (m, m') having at their tops the rosettes (m', m''); the whole combined and arranged as set forth in the drawing.

The leg (E) is curved, large at the top, tapering gradually to (t) where it spreads out into a paw with three toes the large one in front having the claw (t''), and the small ones (p''p'') being the continuations of the projections (p, p') on the sides of the leg; the whole being combined and arranged as seen in figure 2. The front of the leg is ornamented by the small projection (t), between the grooves (l, l'), which meet at (l'') as seen in the drawing.

Upon the octagon frame (D) is the top plate (H) which has its edge ornamented with a moulding made up of the figures (m, m') placed alternately, as seen in figure 1.

What I claim as my invention or production and desire to secure by Letters Patent is the new and ornamental design upon the bed plate A, the lower part (B) of the body of the stove, the grate plate (C), the octagon frame (D) the top plate (H), and the leg (E) of the stove called "The Octagon Cannon," combined, arranged, and having the configuration set forth and fully described in this specification and the

annexed drawings.

In testimony whereof I have hereunto subscribed my name before two subscribing witnesses.
